BEVERAGE DISPENSER

John E. Jeffries, Parma, Ohio, assignor to Aluminum Company of America, Pittsburgh, Pa., a corporation of Pennsylvania

Filed June 11, 1965, Ser. No. 85,699

Term of patent 14 years

(Cl. D2—3)

FIG. 1 is a front elevation of a beverage dispenser embodying my new design;

FIG. 2 is a side elevational view, partly in section, taken from the right in FIG. 1, and;

FIG. 3 is a fragmentary side elevational view, taken from the left in FIG. 1.

I claim:

The ornamental design for a beverage dispenser, substantially as shown.
